ALEXANDER E. BLOCK
By James L. Hopkins,
ATTORNEY.

UNITED STATES PATENT OFFICE

ALEXANDER E. BLOCK, OF ST. LOUIS, MISSOURI

TRUSS FOR SHOES

Application filed November 2, 1928. Serial No. 316,641.

My invention relates to an improved truss for shoes, and has for its object to provide a front bearing-plate, an arched channeled body and a rearwardly-extending terminal butt.

In devising this new article of manufacture I have provided means for keeping the sole, shank and heel of the shoe in alinement with each other and with the shoe-upper.

The rear terminal has all the advantages described in my United States Letters Patent numbered 1,602,793 issued October 12, 1926, wherein it is described and claimed as an integer; in the instant invention that rear terminal also forms an anchorage for the front terminal of the truss.

The front bearing-plate as illustrated has a channeled arched body extending to a rear butt adapted to be seated on the upper face of a heel and to substantially fill the space bound by the inner edges of the indrawn upper materials; the bearing-plate being arranged to be imbedded in the sole structure of a shoe, rearwardly of the line of the anterior 25 metatarsal arch of the wearer.

I have thus provided a true supporting truss for the human foot, extending from beneath the ball of the foot to a point beneath the heel; each of its terminal portions serving as an anchorage for the other.

Incidental to this construction is the reinforcement of the rear butt of my truss by downwardly-depending flanges at each of the marginal edges of the truss; the arched body being channeled throughout, and having downwardly depending flanges as well throughout its rear portion.

The truss of my invention is adapted to be substituted for what is known in the art as the "cottage shank", but by its conformation eliminates the shearing stress exerted on the shoe sole by such cottage shank, and thus obviates the cutting and other danger to the sole which is incident to the employment of 45 the cottage shank.

Drawings

In the drawings—

Fig. 1 is a top plan view of a truss embodying my invention.

Fig. 2 is a side elevation of the same.

Fig. 3 is a longitudinal mid-section of the same taken on the line 3—3 of Fig. 1.

Fig. 4 is a transverse sectional view taken on the line 4—4 of Fig. 1.

Fig. 5 is a transverse sectional view taken on the line 5—5 of Fig. 1.

Fig. 6 is a transverse sectional view taken on the line 6—6 of Fig. 1.

Fig. 7 is a transverse sectional view taken on the line 7—7 of Fig. 1.

Description

The channeled arched-body portion A, at the line indicated as 5—5 in Fig. 1, has its rear upper edges 13—13 (see Fig. 4) bent upon themselves to form the depending flanges 11—11, the depth of which flanges at various points throughout their length is shown by Figs. 5, 6 and 7.

At its rear, the sides of shank portion A are sharply drawn inwardly as indicated by 14—14 in Fig. 1 to form the rear constructed butt B: said butt B being provided with depending side flanges 11—11 which are substantially parallel as shown, except at the rear of said butt B where they converge to the outer edges of the slot 12. The slot 12 is provided to permit the insertion of a screw into the heel.

The butt B is perforated as indicated by 15—15 along its median line to permit the use of nails to secure the butt B to the heel.

The channeled body A is preferably contoured as shown on the drawings; having expanded shoulders 20—20 at or near the rear end 16 of its channel; this for the purpose of creating a broadened bearing surface and providing maximum strength at a line shortly in advance of the breast of the heel of the shoe. The body A also has expanded shoulders 17—17, which are in transverse alinement forwardly of the shoulders 20—20, lending added strength to the truss along the transverse line indicated as 5—5 in Fig. 1 of the drawings, and at the forward end of the rear portion of the channeled body A which has the depending flanges 11—11; the purpose of the shoulder 17—17 being to impart additional strength to the truss at the point where

the upper edges 13—13 are deflected downwardly to form the depending flanges 11—11 (see Figs. 4 and 5).

The bearing plate 10, formed at the front end of the body A is flat, and intended to be imbedded between the layers of material forming the sole of the shoe; and is provided with the perforation 18 to permit the passage of a nail or screw securing the bearing-plate 10 in place between said layers of material.

10 The front edge 19 of the bearing-plate 10 is preferably provided with rounded corners as shown in Fig. 1, to the end of preventing the cutting of the sole-material by the plate 10 during prolonged use of the shoe.

15 The form of my truss illustrated in the drawings is the perfected embodiment of my invention, developed in the actual manufacture of the trusses, and of the shoes in which they are mounted for use, as well as laboratory tests applied to the actual trusses to determine the stresses to which the truss is subjected at various points throughout its length and the resulting requirements of strength in 20 the truss at the point subjected to the greatest stress. However, as the strength of the truss is largely dependent upon the strength of the material employed, as well as upon the contour and configuration of the truss, various changes of form may be effected without 25 departure from my invention as defined in the appended claims.

1 claim—

1. The truss for shoes comprising a rear 35 terminal butt having substantially parallel depending marginal flanges; and an arched channeled body having depending marginal flanges throughout its rear portion, wherein with said butt is integral.

40 2. The truss for shoes comprising a rear terminal butt having substantially parallel depending marginal flanges; and an arched channeled body having depending marginal flanges throughout its rear portion, whereon 45 said butt is mounted, said channeled body being of greater width than said butt, and having a median widened shoulder and a rear widened shoulder.

In testimony whereof I have hereunto affixed my signature.

ALEXANDER E. BLOCK.
